SLIDING TARGET GAME

Filed Jan. 19, 1950

FIG. 1.

FIG. 2.

JOHN O. PRENTISS

BY

John O. Prentiss

UNITED STATES PATENT OFFICE

2,597,671

SLIDING TARGET GAME

John O. Prentiss, San Benito, Tex.

Application January 19, 1950, Serial No. 139,357

5 Claims. (Cl. 273—108.)

1

The present invention relates to a toy or game for either children or adults wherein a target or objective is moved through a predetermined path, and a projectile or missile also moving in a predetermined path is directed toward the path of movement of the target in an endeavor to strike the target before the target moves beyond the range of the missile.

Broadly, the invention comprises a pair of supports disposed and maintained at right angles to each other, each support being provided with a guide wire extending substantially the entire length of the support with one of the guide wires being disposed a slight distance above the other. A target is slidably mounted on one of the wires while a missile is similarly supported on the other wire. A resilient projector may be carried by the support for the missile guide wire in order to impart movement to the missile. The supports are mounted on a suitable pivot whereby tilting movement of the supports will permit the target to slide along the guide wire toward the lowered end, whereupon the missile is directed along its guide wire in an endeavor to hit or strike the target before it passes the juncture of the guide wires.

An object of the present invention is to provide an entertaining toy or game wherein a tethered missile is directed toward the path of movement of a tethered target in an effort to strike the target before the target passes without the zone of contact of the missile.

Yet another object of my invention is to provide a toy or game of the character described wherein one or two persons may operate or play the game simultaneously.

And still a further object of my invention is to provide a toy or game which simulates somewhat the shooting of a bird on the fly, which is simple in structural detail, positive and efficient in operation and which may be easily and inexpensively manufactured.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 is a view in side elevation of the toy or game.

Figure 2 is a plan view of Figure 1.

2

Figure 3 is a fragmental view in side elevation showing one of the resilient projectors, and

Figure 4 is a view generally similar to Figure 3 showing a modification wherein spring means is employed to maintain the guide wire under tension.

Referring to the drawings, it will be noted that there is provided a base 10 adapted to be disposed upon a suitable supporting surface such as a table top, and a pair of arms 11 and 12 disposed at right angles to each other, the arms 11 and 12 being pivotally mounted to the base, as indicated at 13. The pivotal connection 13 includes a post 14 on the base 10, the reduced end of the post being lodged in a recess or socket 15 formed in the lower face of the arm 11. Manifestly, the arms 11 and 12 may have rotational movement as well as rocking movement relative to the base 10.

A post or peg 16 is attached to the arm 11 adjacent each end thereof and a guide wire 17 extends between the posts, the ends of the wire being suitably secured to the posts, as indicated at 18. A missile such as a small ball or marble 19 is provided with a bore 20 extending therethrough in order that the missile may be slidably carried by the wire. A resilient projector 21 is attached to the upper face of the arm 11 a short distance forward of each peg 16 by means of screws 22 which extend through apertures in flange 23 of the projector 21. The upper or free end of the projector is arcuate, as indicated at 24, and is slotted, as shown at 25, to permit the wire 17 to extend therethrough. Manifestly, by moving the projector rearwardly (Figure 4) and by releasing the projector, the ball 19 will be driven along the wire 17.

The arm 12 also includes the same structural elements, and for the purpose of simplicity, the same reference characters will be applied with the exception that they are primed, although it can be seen that the pegs 16' are somewhat greater in length than the pegs 16 to provide the necessary clearance at the cross-over point of the wires 17 and 17'.

To play the game and assuming the target 19' is in the position shown in Figures 1 and 2, the arm 12 is moved downwardly to elevate the opposite end, whereupon the marble 19' will slide along the wire 17' toward the lowered end of the arm. At the same time, the party manipulating the projectile 21 will release the projector in an effort to strike the marble 19' with the missile 19 before the target passes the cross-over point of the wires 17 and 17'. Manifestly, if

the target is not hit, the "shooter" has scored a miss. By rocking or tilting the arm 12 in the opposite direction, the game is now ready for further playing.

It can be seen, therefore, that I have provided a toy which is not only highly entertaining, but which also requires a certain amount of skill in its successful operation. Furthermore, the simplicity of the game will enable persons, regardless of age, to be entertained thereby and no involved rules are required for its playing.

In Figure 4 I have shown a slightly modified construction wherein means are provided for maintaining the wires 17 and 17' in a taut condition. To achieve this end, each of the pegs 16 is notched at its upper end and, as shown at 30, through which the end of the wire 17 extends. The free end of the wire 17 is attached to a coil spring 31, as indicated at 32, and the opposite end of the spring is anchored to the end of the arm 11 by a nail or the like 33. Obviously, these springs 31 will tend to keep the wire in a stretched or tightened position.

If desired, the resilient projector 21 may be provided for each end of the arm 12, thereby permitting the marble 19' slideable on the wire 17' to serve as the missile, and while the marble 19 will be the target. Manifestly, this arrangement will give greater flexibility to the toy and, if desired, two or more marbles may be disposed on the respective guide wires. This latter arrangement would enable two persons to endeavor to strike the target at the same time or substantially the same time.

The invention is not to be confined to any strict conformity with the showing in the drawing, but may be changed or modified so long as such changes or modifications mark no material departure from the salient features of the invention as expressed in the appended claims.

I claim:

1. A toy or game comprising a base, a pair of crossed arms supported by the base, a guide wire secured to and extending longitudinally of each arm in parallel relationship to the arm, a missile slidably mounted on one wire, a target slidably mounted on the other wire, one of said wires being supported a slight distance above the other of said wires, and a projector on the arm supporting the wire having the missile for directing the missile toward the opposite end of the guide wire to strike the target on the other wire before the target passes the cross-over point of the wires when the arms are tilted to allow the target to slide from one end of the wire to the other end thereof.

2. A toy or game comprising a base, a pair of crossed arms pivotally mounted on the base, a peg attached to each arm adjacent the ends of the arm, a guide wire secured to said pegs in proximity to the upper ends of the pegs and

extending in parallel relationship to the arm, the pegs of one arm being of greater length than the pegs of the other so that the wire secured to the pegs of greater length will be disposed a slight distance above the other guide wire, a missile slidably mounted on one guide wire, a target slidably mounted on the other guide wire and a resilient projector secured to one end of the arm supporting the missile guide wire for driving the missile along the wire to strike the target on the other wire before the target passes the cross-over point of the wires when the arms are rocked on the pivot to elevate one end of the arm carrying the target.

3. A toy or game as claimed in claim 2 wherein spring means is operatively connected to each end of said guide wires and said arms to maintain the wires in a taut condition.

4. A toy or game comprising a pair of crossed guide wires supported at right angles to each other with one of said guide wires disposed a slight distance above the other of the said wires, a missile slidably mounted on one wire, a target slidably mounted on the other wire, and a projector for one of said wires for directing the missile toward the opposite end of the wire to strike the target on the other wire before the target passes the cross-over point of the wires when the wires are tilted to allow the target to slide from one end of the wire to the other end thereof.

5. A game device comprising a pair of crossed arms adapted to be supported at right angles to each other, a guide wire secured to and extending longitudinally of each arm in spaced parallel relation to the arm with one of said guide wires located a slight distance above the other of said wires, a missile slidably mounted on one wire, a target slidably mounted on the other wire, and projector means cooperating with the wire having the missile thereon to direct the missile along its wire toward the opposite end of the wire to strike the target on the other wire before said target passes the crossover point of the wires when the arms are tilted to allow the target to slide from one end of the wire to the other end thereof.
